UNITED STATES PATENT OFFICE.

WALTER M. JACKSON, OF PROVIDENCE, RHODE ISLAND.

RECEPTACLE FOR HOLDING GASES UNDER PRESSURE.

SPECIFICATION forming part of Letters Patent No. 244,245, dated July 12, 1881.

Application filed February 21, 1881. (No model.)

To all whom it may concern:

Be it known that I, WALTER M. JACKSON, of Providence, in the county of Providence, and in the State of Rhode Island, have invented certain new and useful Improvements 5 in Receptacles for Holding Gases Under Compression; and I do hereby declare that the following is a full, clear, and exact description thereof, reference being had to the accompanying drawings, and to the letters of reference marked thereon, making a part of this specification.

This invention relates to certain improvements in receivers or holders in which gas or 15 gases of any description can be condensed and stored under great pressure.

Heretofore all receivers or holders for this purpose have been constructed of metal, such as brass, steel, or iron; but they have proved 20 defective and impracticable for the purpose, owing to the porosity of the metal, which permits the gas to gradually escape through the walls of the receiver.

The object of my present invention is to ob- 25 viate these defects and provide a receiver or holder that will be almost, if not wholly and absolutely, impervious to gas, and in which a large amount of gas can be condensed and im- prisoned and drawn off as required for use.

To this end my invention consists of a receiver or holder constructed mainly of paper, and saturated with a suitable composition or substance to render it impervious to gases, as 30 more fully hereinafter specified.

I accomplish the above-mentioned objects 35 by the apparatus illustrated in the accompanying drawings, in which—

Figure 1 illustrates a perspective view of my improved receiver or holder; Fig. 2, a de- 40 tached view of the main portion of the receiver and its heads, and Fig. 3 a detached view of one of the bolts and screw-nuts by means of which the heads are bolted to the body.

The letter A indicates the main portion or 45 body of the receiver or holder, which is constructed, preferably, of one continuous piece. This is wrapped around a rotating arbor or

mandrel, and during the wrapping is saturated continuously, in any convenient manner, 50 with a suitable compound or substance which will fill the pores of the paper, strengthen it, and render it impervious to gas. I have found in practice that a mixture of gelatine and glycerine, in about the proportions of one part of 55 gelatine to twenty parts of glycerine, forms a compound well adapted to this purpose for general uses; but I do not limit myself to such proportions, as they may be varied considerably without departing from this part of my 60 invention.

The arbor or mandrel is preferably disjointed or disconnected between its ends, so that after the body of the receiver or holder is made it 65 can be readily removed.

The letter B indicates a flange, one at each end of the body of the receiver or holder. These are preferably turned up during the process of rolling, but they may be formed in any other convenient manner. To these flanges 70 are fitted the heads C D. The heads C are struck up in concavo-convex form out of paper, and the heads D of similarly-shaped steel disks, and the whole are bolted securely to the flanges by means of the longitudinal screw- 75 bolts E, provided with the screw-nuts F.

The joints between the heads and the flanges of the receiver or holder may be made tight by means of any suitable cement or composi- 80 tion.

The letter G indicates a pipe through which the compressed gas may be drawn off for use. This is provided with a check or regulating valve, H, by means of which the gas may be delivered from the receiver or holder at a uniform pressure, no matter what the pressure may be in the receiver.

The receiver and holder as thus constructed I have found by practice will contain practically one thousand cubic feet of gas to one 90 cubic foot of capacity, which can be delivered, by use of the check or regulating valve, at a uniform pressure of three inches of water or thereabout, so long as the pressure in the receiver or holder exceeds three inches of water-pressure.

Having thus described my invention, what I claim, and desire to secure by Letters Patent, is—

1. A receptacle or holder for compressed gas or gases, constructed of paper combined with gelatine and glycerine, substantially as specified.

2. The combination, with the body of the receptacle or holder and the paper heads there-

of, the steel heads and bolts for securing the same together, substantially as set forth.

In testimony that I claim the foregoing I have hereunto set my hand this 17th day of February, 1881.

WALTER MARSH. JACKSON.
